UNITED STATES PATENT OFFICE.

WILLIAM P. TROWBRIDGE, OF NEW HAVEN, CONNECTICUT.

STAMP-PROTECTOR.

SPECIFICATION forming part of Letters Patent No. 378,119, dated February 21, 1888.

Application filed October 17, 1887. Serial No. 252,515. (No model.)

To all whom it may concern:

Be it known that I, WILLIAM P. TROWBRIDGE, a citizen of the United States, residing at New Haven, in the county of New Haven and State of Connecticut, have invented certain new and useful Improvements in Protectors for Postage, Revenue, and other Stamps, Court-Plaster, and like articles having surfaces which are rendered adhesive by moisture; and I declare the following to be a full, clear, and exact description of the same, reference being had to the accompanying drawings, forming part of this specification, and to the letters and figures of reference marked thereon.

When postage-stamps and like articles provided with gummed surfaces are carried in the pocket, it is found that such gum is rendered moist and adhesive by the heat and moisture of the body, thus causing the stamps to stick to each other or to the surfaces with which they may happen to be in contact. This is especially true during the moist and hot days of the summer months, and is the cause of considerable annoyance and loss. Under such circumstances it is often found that the stamps will absorb the moisture from the atmosphere, and thus cause them to adhere to each other, even though they are not carried in the pocket, but simply stored in some convenient receptacle.

To provide simple and effective means to avoid this difficulty is more especially the object of my present invention.

I have found that if the gummed surface of the stamp or other article be placed in contact with a suitably-roughened surface—as, for example, the rough surface of ordinary sand-paper—all trouble from the adhesion of the stamp will be entirely avoided even though the gummed surfaces be appreciably moistened. When such gummed or adhesive surfaces are placed in contact with such roughened surface, the actual contact of any appreciable area is prevented by the multitude of small points or projections which are presented to the gummed surface. No adhesion can therefore take place except at these points, the total effect of which is practically inappreciable.

In the accompanying drawings I have shown several forms in which my invention may be embodied.

Figure 1 represents, on an enlarged scale, the cross-section of part of a stamp in contact

with a roughened surface. Fig. 2 represents a simple case for carrying stamps in the pocket. Fig. 3 represents a similar case for carrying a larger number of stamps. Fig. 4 represents an ordinary pocket-book or portmouniae with a compartment provided with non-adhesive surfaces in accordance with my invention. Fig. 5 shows a form of case or book with non-adhesive surfaces for storing or transporting stamps in larger quantities.

The principle of my invention is illustrated in Fig. 1, in which A represents the cross-section of part of a postage stamp or other article provided with a gummed or adhesive surface. This adhesive or gummed surface is protected by being placed in contact with a suitably-roughened surface, B. Though I may use for this purpose any material having a suitably-rough surface without departing from the spirit of my invention, I prefer to use ordinary sand-paper or other suitable material provided with a sanded surface. This sand-paper or other roughened surface presents a multitude of small points or projections, *pp*, to the gummed surface of the stamp, thus preventing the contact of any appreciable area, and thereby avoiding the adhesion of the stamp or other article. Instead of the roughened surface used in this connection being provided with projections presenting points to the contact of the adhesive surfaces, they may be provided with ridges or corrugations presenting their edges to the contact of the adhesive surfaces, thus in similar manner preventing the contact of any appreciable area, and thereby the adhesion of the stamp.

In Fig. 2 I have represented a simple and convenient form of pocket book or case for carrying stamps. It consists, essentially, of a suitable book or case, C, of paper, leather, or other material. The inner surfaces, D, of this case are suitably sanded or roughened, or else provided with sheets of ordinary sand-paper. The postage-stamps P are carried in this book with their adhesive or gummed surfaces in contact with the roughened surfaces D.

In Fig. 3 I have shown a similar book or case, except that it is provided with extra leaves of sanded or roughened paper, thereby largely increasing the capacity of the book or case.

Fig. 4 represents an ordinary pocket-book,

one compartment, F, of which is lined with sand-paper or other suitable material provided with a roughened surface to prevent the adhesion of the postage-stamps. This lining may 5 be made removable, or a simple book or case, as shown in Fig. 2 or Fig. 3, may be made of such size as to be conveniently carried in this compartment of the pocket-book.

In Fig. 5 I have shown a larger book or case, 10 which may conveniently be used for storing or transporting stamps or other articles having adhesive surfaces in larger quantities. It consists simply of a large number of sheets of sand-paper or other material provided with a suitably-roughened surface, G, which are held together between covers I by a suitable backing or fastening, H, somewhat like an ordinary book. The postage or other stamps are placed 15 between the sheets of sand-paper G, which thoroughly protects them and prevents all adhesion of their gummed surfaces.

It will of course be readily understood that I can, without departing from my invention, use such sheets provided with sanded or roughened surfaces without their being secured or fastened in any particular manner. Thus I can 20 fully protect stamps by simply packing them 25

in sheets alternately with sheets of sand-paper in a box or other convenient manner. The various devices which I have described are intended merely to illustrate a few convenient forms in which my invention may be embodied. 30

The method herein described of protecting postage-stamps and similar articles will be made the subject-matter of a future application. 35

What I claim as my invention is—

1. A protector for postage-stamps and other articles having gummed or adhesive surfaces, provided with a surface suitably roughened 40 for receiving the contact of said gummed or adhesive surfaces, substantially as shown and described.

2. A protector for postage-stamps and other articles having gummed or adhesive surfaces, provided with a series of sheets of suitably-roughened material for receiving the contact 45 of said gummed or adhesive surfaces, substantially as shown and described.

WILLIAM P. TROWBRIDGE.
